Inventor:

Emil O. Starke

UNITED STATES PATENT OFFICE

EMIL O. STARKE, OF CHICAGO, ILLINOIS

HARP

Application filed August 5, 1929. Serial No. 383,569.

The present invention consists in providing a harp with structural means embodied within the acoustic chamber for anchoring the strings of the harp. This structural means is called the tail-piece for the strings.

The object of this tail-piece is to relieve the tremendous strain effecting the warping of the sounding board through which the strings pass through eyelets in the usual manner and hence to the usual so-called action mechanism located upon the neck of the harp.

Another object of the tail-piece is to improve the tone sounds of the harp due to the special arrangement or acute alignment of the strings from the said tail-piece in relation to the passage through the eyelets in the sounding board.

A further object of this tail-piece is to cause a somewhat downwardly and rearwardly thrust or pressure of the sounding board; i. e., due to the path of the strings at approximately right angles, thus retaining the sounding board in balance and permanent position when all the strings are in proper tensional tune.

And further, by the use of this tail-piece embodied in a harp for anchoring the strings, the quality of more exact, full and half tones is accomplished. Therefore it will be understood by the foregoing objects attained, it will be unnecessary to readjust the action-mechanism as often as is now practiced.

With these and other objects in view, as will more fully appear as the description proceeds, the invention consists of certain constructions, arrangements and combinations of parts that I shall hereinafter fully describe and claim.

For a full comprehension of my invention, reference is to be had to the following description and accompanying drawings, in which:

Figure 1 is a perspective view of a harp,

a portion being broken away and illustrating the embodiment of my invention;

Fig. 2 is an enlarged detailed view taken through the acoustic chamber illustrating the string tail-piece to which the ends of the strings are fastened in the usual way, together with associated parts of usual construction;

Fig. 3 is a horizontal transverse cross sectional view showing very clearly my invention near the base of the acoustic chamber; and

Fig. 4 is a similar view, but taken at the upper portion of same.

The reference character A represents the harp as an entirety comprising the acoustic chamber A' of usual construction. B is the laminated sounding board provided with an inner string bridge C and an outer string bridge D. The usual frame work, as designated by the reference characters E and F, respectively, are of usual construction. The frames E, E are constructed lengthwise within the acoustic chamber, and the frames F, F run transversely to act as reinforcing ribs 70 of the acoustic chamber structure.

Interposed between the rear wall of the acoustic chamber and the sounding board and its associated parts is located the string tail-piece H, V-shaped in cross section as illustrated in Fig. 3 of the drawings. The above mentioned string tail-piece H is made of suitable metal material, and tapers from the bottom to the top slightly for the reason that the greatest tension of the strings exists at the base, and the string tail-piece H may be supported both at the top and bottom, as shown, and supported or reinforced as by intermediate metal saddle-strips G fastened, as shown, on the main frames E, E.

Heretofore, in practice, the strings reaching from the neck portion of the harp have always been anchored to the sounding board directly and tends to shorten the life of the harp by warping the sounding board, but in

my invention it will be understood by reference to the drawings that I support the strings K indirectly to the sounding board and to a rigid anchoring means, as by the string tail-piece H provided with a plurality of button-hole slits h for the insertion of the knotted string ends k of the strings K. The strings K are then supported and pass through the several holes provided in the inner bridge piece C, sounding board B, and the outer bridge D containing the usual eyelets, respectively, and then to the action mechanism of usual construction. No effort has been made to illustrate this mechanism, as it is well-known science.

It will be noticed that the strings K vary somewhat in respect to alignment from end to end; i. e., from the action mechanism at the neck portion to the sounding board they all lie parallel, and pass therethrough at an acute angle and then almost back again to the original angle, thus producing a zig-zag course.

In this peculiar arrangement of the strings, together with the rigid metal tail-piece that lengthens the life of the harp, instead of a warping effect as occurs in harps now manufactured, I attain a great achievement, in that the above described arrangement retains the sounding board in an original and permanent position as a rearwardly and downwardly thrust is developed as the strings are being made taut and in tune for playing, thereby practically balancing the sounding board intermediately between the action mechanism and the tail-piece H.

And further, by the above described arrangement of parts and elements so associated a more harmonious and sustained quality of tones is attained.

The above are the distinctive features of my invention and while I have herein shown and particularly described the preferred embodiment of my invention, I do not wish to be limited to the precise details of construction shown, as many changes may readily be made without departing from the spirit of my invention. But having thus described my invention, I claim as new, and desire to secure by Letters Patent, the following:

1. In a harp, a base, a pillar, a neck for the action mechanism for the strings, an acoustic chamber having a sounding board, eyelets arranged in said sounding board through which pass the strings to a string anchor tail-piece in a zig-zag course and a plurality of reinforcing strips for intermediate support of said tail-piece within the acoustic chamber, as set forth.

2. In a harp, a base, a pillar, a neck for the action mechanism for the strings, an acoustic chamber having a sounding board, eyelets arranged in said sounding board through which pass the strings to a tapered metal V-shaped string anchor tail-piece in a

zig-zag course, terminating within the acoustic chamber for preventing the warping of the sounding board when the strings are in tensional tune, as set forth.

3. In a harp, a base, a pillar, a neck for the action mechanism for the strings, an acoustic chamber having a sounding board, eyelets arranged in said sounding board through which pass the strings to a string anchor tail-piece in a zig-zag course, terminating within the acoustic chamber for preventing the warping of the sounding board when the strings are in tensional tune, as set forth.

E. O. STARKE.
